UNITED STATES PATENT OFFICE.

JOHN F. RICHMOND, OF ALBANY, NEW YORK.

IRONING-TABLE.

SPECIFICATION forming part of Letters Patent No. 289,561, dated December 4, 1882.

Application filed June 15, 1883. (No model.)

To all whom it may concern:

Be it known that I, JOHN F. RICHMOND, a citizen of the United States, residing at Albany, in the county of Albany and State of New York, have invented certain new and useful Improvements in Ironing-Tables, of which the following is a specification, reference being had therein to the accompanying drawings.

10 This invention relates to ironing-tables; and it consists in certain improvements in adjustable tables, as hereinafter shown, described, and claimed.

In the accompanying drawings, Figure 1 represents a plan of an ironing-table having my improvements. Fig. 2 is a side view of the same. Fig. 3 is a vertical longitudinal section of the table. Fig. 4 is a side view, showing the table closed. Fig. 5 is a plan view 20 of the closed table inverted.

A designates the top of the table, forming the ironing-board, which is hinged at one end to the frame, this being usually effected by fastening the end of the board to a cross-bar, 25 *a*, which has bearings in apertures in the inclined bars *B* and *C*, the parts having pivotal connection. The other end of the board *A* rests on a cross-bar, *b*, which is fixed to the ends of the inner inclined bars, *B'*, a pin, *c*, on bar *b* entering an aperture in the board *A*. The lower ends of the two bars *C* are pivoted at *d* to the bars *B'*, which, with the bars *B*, form the main supporting parts of the frame. The two bars *C'*, near the opposite end of the 30 frame, have their upper ends pivoted to the inner bars, *B'*, and their lower ends pivoted at *e* to the outer bars, *B*, as shown, the pivotal connections of parts being intended to allow the closing of the frame, as hereinafter set forth. The cross-strips *f* and *g* connect corresponding parts in opposite sides of the frame, and form braces to strengthen it.

D indicates two short bars or connecting-pieces, one being located at each side of the 45 frame, and having one end pivoted at *s* to an outer bar, *B*. The other end is fastened to one end of a rod, *h*, extending across the frame, and passing through the slots *i* in the inner bars, *B'*. One or more notches, *n*, in each slot 50 are intended as rests for the rod *h*, when the

table is adjusted for use, (see Fig. 2,) a spring, *m*, on each bar *B'* serving to retain the rod in place, and thus hold the parts in position as desired. A notched guard-plate, *o*, fixed in each bar *B'*, prevents wearing of the notches 55 by the rod *h*.

The operation of opening or closing the frame is very simple. In opening and adjusting it for use, the board *A* is raised on its hinges, and the frame is spread by handling 60 the cross-bars *a* and *b*. The rod *h* moves along in the slots *i* under the yielding springs *m*, and rests in two notches, *n*, where it is retained by the springs, and the board *A* is left with its forward end resting on cross-bar *b*, 65 the pin *c* entering a hole, *p*, in the board. In closing the table, the board *A* is lifted from bar *b*, and the upper extremities of bars *B* and *B'* pressed downward, the springs yielding to the pressure caused by the pieces *D* drawing 70 the rod *h*, and the several parts of the table are brought together in the form shown in Figs. 4 and 5, and may be secured by turning the button *r* over rod *h*, and the table thus closed may be conveniently laid away or hung up or 75 packed for transportation.

I claim—

1. An adjustable table having supporting-bars *B*, with pivoted pieces *D*, holding a cross-rod, *h*, in combination with slotted supporting-bars *B'*, connecting-bars *C* and *C'*, and a top board hinged to two of the supporting-bars, the parts being constructed substantially as and for the purposes described. 80

2. An adjustable table having a hinged 85 board, *A*, supported substantially as shown, the main bars, *B*, hinged to the table-top, bars *B'*, provided with notched slots *i*, and connecting-bars *C* and *C'*, in combination with the pieces *D*, pivoted to frame *B*, rod *h*, mounted 90 on said pieces and passing through slots *i*, and the retaining-springs, substantially as set forth.

In testimony whereof I affix my signature in presence of two witnesses.

JOHN F. RICHMOND.
